G. F. BULL.
LAWN MOWER AND THE LIKE.
APPLICATION FILED JULY 8, 1921.

Patented May 23, 1922.

UNITED STATES PATENT OFFICE.

GEORGE F. BULL, OF BIRMINGHAM, ENGLAND, ASSIGNOR OF ONE-HALF TO CHARLES H. PUGH, LIMITED, OF BIRMINGHAM, ENGLAND.

LAWN MOWER AND THE LIKE.

1,416,784.

Specification of Letters Patent. Patented May 23, 1922.

Application filed July 8, 1921. Serial No. 483,126.

To all whom it may concern:

Be it known that I, GEORGE FREDERICK BULL, subject of the King of Great Britain, residing at Birmingham, England, have invented certain new and useful Improvements in Lawn Mowers and the like, of which the following is a specification.

This invention relates to lawn mowers and the like, of that type comprising a number 10 of revolving cutter-blades carried by spacing discs mounted upon a central spindle.

The object of the present invention is to provide improved and more efficient means for securing the blades to the spacing discs.

15 The invention consists essentially in forming the spacing discs with a series of slots with which the blades are engaged, and in displacing the metal of the discs adjacent to the edges of the slots against the sides 20 of the blades, so that the latter are rigidly secured in position. The blades may be either formed with parallel or with taper sides and the slots shaped to correspond; or a taper-sided blade may be fitted within 25 a parallel-sided slot, and the metal adjacent to the slot closed against the sides of the blade. In case where a taper-sided blade is employed the thicker portion of the blade is arranged to form the inner or non- 30 cutting edge.

Figure 1 of the accompanying drawings represents an elevational view of a series of cutting blades fixed to the spacing discs in accordance with this invention, the blades 35 being formed with parallel sides and engaging with parallel-sided slots in the said discs.

Figure 2 is a cross-section on the line 2—2 Figure 1, upon a larger scale.

40 Figure 3 shows a longitudinal section through the end of one of the blades, and through one of the spacing discs.

Figure 4 shows one of the blades in the act of being engaged with the slot in the 45 spacing disc, the said blade being shown in cross-section.

Figure 5 represents an alternative method in which the blade is formed with taper sides and is engaged with a parallel sided 50 slot in the spacing disc, showing the slot prior to the metal adjustment to the sides of the same being forced against the sides of the blade.

Figure 6 is a view of this alternative 55 method after the metal adjacent to the sides

of the slot has been forced against the blade.

Figure 7 represents a longitudinal section through one end of a blade which is formed with recesses on either side, into which the metal at each side of the slot in the spacing disc is forced. 60

Figure 8 is a section on 8—9 Figure 7.

Figure 9 shows an arrangement in which both the slot and the blades are formed with taper sides, the blade being engaged with 65 the slot endwise.

The same reference numerals indicate corresponding parts in each of the figures.

Referring to Figures 1 to 4 of the drawings, the cutter comprises a series of curved 70 blades 1 arranged spirally around a central spindle 2. The blades 1 are of a uniform flat rectangular cross-section and are carried at intervals in their length by spacing discs 3 rigidly fixed to the spindle 2. Each 75 of the discs 3 is formed with a number of radial parallel sided slots 4 (Figure 4) corresponding to the number of blades, and of a width approximately equal to the thickness of the blades, the said slots being arranged at equal distances apart and extending to the outer periphery of the disc, as shown. Each of the blades 1 is engaged with the respective slots in the disc 3 so that its cutting edge is presented outwards, 80 the slots being of a length slightly less than the width of the blade so that the cutting edge projects beyond the outer periphery of the discs. After the blades have been engaged within the slots in the supporting 85 discs the metal of the discs adjacent to the sides or edges of the slots is displaced so that it is closed against the sides of the blades, thus rigidly securing the latter in position. 90

Referring to Figures 5 and 6, instead of the blades 1 being of a uniform cross-section as above described, they may be formed with taper sides, the thicker portion of the blade forming the rear edge, as shown. The slots 100 4 in the supporting discs 3 are formed with parallel sides, the blades 1 being engaged with the respective slots, when the metal adjacent to the sides of the latter is displaced against the sides of the blades in a similar 105 manner to the above described.

If desired the blades 1 may be formed with recesses 5 at points which come adjacent to the sides of the slots in the discs 3 when the said blades are fitted in position. 110

The metal displaced from the sides of the slots is thus forced into the recesses 5 and serve to lock the blades firmly in place, as shown in Figures 7 and 8.

5 As shown in Figure 9, both the blade 1 and the slot 3 may be of a taper formation. In this case the blades are engaged endwise with the slot, and then secured, by displacing the metal at the sides of the slots.

10 If desired one side only of the blade may be inclined, the blade being either engaged with correspondingly shaped slots, or with parallel sided slots.

Having fully described my invention what 15 I desire to claim and secure by Letters Patent is:—

1. A lawn mower comprising a number of revolving cutter-blades, spacing discs carrying the said blades and having slots 20 therein with which the blades are engaged, and means for securing the blades in the slots, the said means consisting of the metal of the discs adjacent the slots displaced against the sides of the blades so as to hold 25 the latter securely and firmly in position.

2. A lawn-mower comprising a number of parallel-sides revolving cutter-blades, spacing discs carrying the said blades and having parallel-sided slots therein with which 30 the blades are engaged, and means for securing the blades in the slots, the said means consisting of the metal of the discs adjacent

the slots displaced against the sides of the blades so as to hold the latter securely and firmly in position.

35

3. A lawn-mower comprising a number of revolving cutter-blades, spacing discs carrying the said blades and having slots therein with which the blades are engaged, means for securing the blades in the slots, the said means consisting of the metal of the discs adjacent the slots displaced against the sides of the blades and into recesses formed in the latter adjacent the slots, so as to lock the blades securely and firmly in position.

45

4. A lawn-mower comprising a number of parallel-sided revolving cutter-blades, spacing discs carrying the said blades and having parallel-sided slots therein with which the blades are engaged, means for securing the 50 blades in the slots, the said means consisting of the metal of the discs adjacent the slots displaced against the sides of the blades and into recesses formed in the latter adjacent the slots, so as to lock the blades securely 55 and firmly in position.

In testimony whereof I have hereunto set my hand in presence of two subscribing witnesses.

GEO. F. BULL.
